WIRE LINE ENDS AND METHOD OF FORM-
ING SAME

Earl E. Wherry, Oklahoma City, Okla.

Application November 29, 1935, Serial No. 52,251

13 Claims.

(Cl. 140—71)

This invention relates to wire line ends and methods of forming same.

In industry, it is frequently necessary to thread a multiple wire cable or line through a restricted opening or a plurality of adjacent openings, such as the cable employed in the rotary drilling of oil wells and operating through the hoisting block strung from sheaves at the derrick's crown.

Another example is the calf or casing line threaded between the sheaves of a hoisting block and the plurality of sheaves at the derrick crown. It has been found very difficult to thread such lines or cables through the blocks and over the sheaves because of the restricted spaces.

A third example of its use is in threading wires of guard lines through the holes provided in concrete or metal posts positioned along highways at curves and the like.

The principal object of the invention is to provide a novel wire line end shaped to be readily threaded through restricted openings.

Another important object is to provide a wire line end having a tapered nose or extremity.

Still another important object is to provide such a wire line end having its greatest width no greater than the diameter of the line itself.

Another important object is to provide methods for the production of such a wire line end.

Other objects and advantages of the invention will be apparent during the course of the following detailed description, taken in connection with the accompanying drawings, forming a part of this specification and in which drawings:—

Figures 1, 2, 5, and 7 are perspective views and Figures 3, 4, 6, 8a and 8b are sections, all being of a wire line in various stages while being provided with the novel wire line end, Figures 3, 4, 6 and 8b being upon their respective lines of Figures 2, 5, and 7, and Figure 8a being on substantially the same line as Figure 8b but showing a rough surface, which rough surface has been smoothed as in Figure 8b. Figures 8a and 8b are sections upon a somewhat enlarged scale.

Figures 9, 10, 13, and 15 are perspective views and Figures 11, 12, and 14 are sections taken upon their respective lines of Figures 10 and 13, all being of a wire line and illustrating another method of producing the novel wire line end, the finished end being illustrated in Figure 15.

Figures 16, 17, 19, 20, and 21 are perspective views and Figure 18 a section on the line 18—18 of Figure 17, all being of a wire line and illustrating still another method of producing the novel wire line end, the completed end being shown in Figure 21.

Figures 22, 23, and 25 are perspective views and Figure 24 a section substantially upon the line 24—24 of Figure 23, these figures being of a wire line and illustrating another method of producing the novel wire line end, the completed end being shown in Figure 25.

In the drawings, wherein for the purpose of illustration is shown both the preferred and modified forms of the invention and wherein similar reference characters designate corresponding parts throughout the several views, the wire line is designated in each form as A, and the novel line wire ends are designated generally B, C, D, and E.

The wire line A comprises a plurality of bendable and flexible wire strands shown, by way of example, as numbering seven and numbered 30 to 36 inclusive, preferably twisted or woven into a line having a rounded cross section as shown, for example, in Figures 3, 11, 18, and 24. But, without invention, a conventional wire line may be employed having the individual strands of a cross section other than circular or made up of a plurality of smaller wire strands, such wire lines being well known in the art. Preferably, the line is so laid that one strand, 30 for example, is substantially diametrically opposite another strand, 33 for example, at any certain portion of the lays, as is shown in Figures 3 to 6, 11, 12, and 18. When a strand is cut back from the free end 37 of the wire line A and removed, a spiral groove remains, and when two or more adjacent strands are cut back from the wire line end 37, a spiral groove remains, each groove being defined by a portion of the surface of adjacent strands.

The wire line ends B, C, D, and E have features in common and substantially similar corresponding parts or portions, so that similar reference characters will designate these parts throughout the views.

Each wire line end B, C, D, and E comprises an eye portion 40, preferably much longer than wide. In fact, so that the wire line can be readily threaded as set out, the greatest width of the eye portion 40 is no greater than the diameter of the line A. Conversely, the diameter of the line A is at least as great as the greatest width of the eye portion 40. The eye portion 40 is preferably oval when viewed through the eye 41 and has its outer extremity of nose 42 rounded by the provision of a bight 43 at this end of the eye portion. This nose may be provided with a ferrule or cap 44. Extending from this bight 43 are arms 45 which define a part of the eye 41. The opposite end of the eye portion 40, where it, or the arms 45,

join the wire line A preferably is encircled by a coat 46 of metal which extends, as well, over the faces of the free ends of any wire strands 30 to 36 which may terminate there, thus providing a cap for such free ends. It is preferred that this coat 46 have no rough nor sharp portions.

Now as for the method for constructing the wire line end B, shown in Figures 1 to 8b inclusive. A number of the strands of the wire line A are cut back from the free end 37 to the points 50 so that there is one or more strand remaining extending beyond the points 50 on the line A. For example, the strands 30 and 35 may be severed at the points 50 leaving, in the example shown, strands 31 to 34 and 36. Thereupon, a number of the remaining strands are cut back to the points 51 which are intermediate the end 37 and the points 50 of the line A. In the example shown, strands 31, 34, and 36 are so severed, leaving strands 32 and 33. It will be noted in Figure 3 that the points where these strands 32 and 33 lay in the line A are diametrically opposite the points 50. The length of the strands 32 and 33, measured from the points 51 should be such that, when the strands 32 and 33 are untwisted or straightened out and then each bent or doubled upon itself to form the bight 43, arms 45 and eye 41, the free ends of the strands 32 and 33 may be inserted into the spiral groove left 30 in the line A by the removed portions of the strands 30 and 35, so that the free ends of the strands 32 and 33 will abut the points 50, as shown particularly in Figure 5. The free ends of the strands 32 and 33 may be united to the points 50 of the strands 30 and 35 in any approved way, such as by a weld 52 which is preferably smoothed down.

The cap or ferrule 44 as well as the coat 46 may be provided also by welding, and the rough weld, as shown in Figure 8a, smoothed down, as shown in Figure 8b.

Referring now to the method of providing the wire line end C, shown in Figures 9 to 15, a section of a single wire strand, for example the strand 35, is cut back from the free end 37 of the wire line A to the point 50, leaving strands 30 to 34 and 36 untouched. Thereupon, all but one strand is cut back to the points 51 which are intermediate the end 37 and the point 50. Preferably, all but strand 32 are so cut back so that the strand which lies diametrically opposite the point 50 will be strand 32. The length of the strand 32, measured from the point 51 should be such that when it is doubled back, as described in the construction of the line end B, its free end may be laid into the spiral groove left by the removal of the severed portion of strand 35, with its free end in abutment with the point 50 and secured as heretofore set out. Preferably, the same 60 welds are made in the formation of the line end C as in the construction of the line end B.

In the form of the line end D, shown in Figures 16 to 21, a somewhat different procedure is followed to provide substantially the same wire 65 end heretofore described. In this case four strands such as 30, 32, 33, and 35, are cut back from the free end 37 of the line A to the point 50, leaving strands 31, 34, and 36 untouched. It will be noted in Figure 18 that the several points 50 70 are at diametrically opposite sides of the line A. Now, by laying, in the two spiral grooves provided by the removal of these portions of strands 30, 32, 33, and 35, the free ends of the arms 70 of a pair of hairpin-like wire members, each member

having a bight 71 joining the arms 70, so that the free ends of the arms 70 are in abutment with the points 50, and then securing the free ends to the line A, an eye portion is provided which may be additionally treated, as by welding, to provide the cap or ferrule 44 and coat 46. Without invention, but two opposite strands may be cut back as stated and a single hairpin-like member substituted for the pair of similar members described.

In the final method of constructing the novel line end, the procedure is illustrated in Figures 22 to 25. Here, preferably three strands, such as strands 32, 35, and 36 are severed at the points 50 spaced inwardly from the free end 31 of the line A, leaving the projecting adjacent strands 30 and 31 and strands 34 and 33. Two of the points 50 are, as heretofore, preferably on diametrically opposite sides of the wire line A and the third point is at the axis of the line, as shown in Figure 24. Now, the projecting portions of the strands 30 and 31 and 33 and 34 are untwisted and their extremities, which constitute the free end 37 of the wire line A, are paired, curved and united in pairs so that a bight portion is formed by the 25 united pairs. Preferably, the free ends of the strands 30, 31, 33, and 34 are united by welding so that the cap or ferrule 41 is also formed by the weld. Additionally, the coat 46 is applied, as by welding, more particularly as heretofore set out. 30

It is apparent that the steps of cutting back to the points 50 and then cutting back to the point or points 51 may be reversed without affecting the method, and that the several welds, if welding is employed, may be made in rotation different from that set out herein, without departing from the spirit of the invention.

The tapered forward end or nose of the wire line end enables it to be readily inserted into a confined space, such as that between a sheave and 40 a block, under derrick sills, or through the rough surface of holes in highway guard posts. Because, in no case is the greatest width of the eye portion of this novel wire line end greater than the diameter of the line itself, any space which 45 will accommodate the line will also accommodate the eye portion, yet a strong, sturdy construction is provided.

It should be understood that this wire line end is provided not to take any exceptionally heavy 50 load but so that it may be linked, for example, to a chain, or may be easily wired to another line in order to cause the line of which it forms a part to follow over the sheave in taking off or putting on a casing line or hoisting cable. In other words, the novel line end is provided more particularly for threading purposes.

The coat 46 has a dual function. Not only does it secure the strands, forming the eye portion, to the line A at the inner end of the eye 60 41, but it also covers the more or less ragged or sharp edges at the extremity of the severed strands, so that they will not injure the workmen, damage the rope or line attached to the line A, nor catch upon the walls of the confined spaces through which the end must pass.

Various changes may be made to the form of invention as well as the steps in the method, herein shown and described, without departing 70 from the spirit of the invention or the scope of the claims.

What is claimed is:

1. In a wire eyed end of a wire line, an eye portion comprising at least one wire strand, sub- 75

stantially integral with said line, said line having a diameter at least as great at all times as the greatest width of said eye portion.

2. In a wire eyed end of a wire line, an eye portion comprising at least one strand of bendable wire, substantially integral with said line, said line having a diameter at least as great at all times as the greatest width of said eye portion, the outer extremity of said eye portion being

10 tapered.

3. In an eyed end of a multiple wire strand line, an eye portion of wire strand having a bight and spaced apart arms, the ends of said arms opposite said bight joining said line at points on substantially diametrically opposite sides of said line.

4. In an eyed end of a multiple wire strand line, an eye portion of wire strand having a bight and spaced apart arms, the ends of said arms opposite said bight joining said line at points on substantially diametrically opposite sides of said line, said line having a diameter at least as great at all times as the greatest width of said eyed portion.

25 5. In an eyed end of a multiple wire strand line, an eye portion of wire strand having a bight, at the outer extremity of said eye portion, and spaced apart arms extending from said bight, the ends of said arms opposite said bight joining said line at points on substantially diametrically opposite sides of said line, and means both securing said arms to said line and providing a cap over said line at the inner extremity of said eye.

6. In an eyed end of a wire line, an eye portion formed from the material comprising said line, said line having a diameter at least as great at all times as the greatest width of said eye portion.

35 7. In an eyed end of a multiple wire strand line, an eye portion formed from a portion of said strands, said line having a diameter at least as great at all times as the greatest width of said eye portion.

40 8. The steps in the method of providing a bendable eye portion of bendable wire to an end of a multiple strand wire line which comprise forming from bendable wire a bight and spaced apart arms from said bight to said line, and positioning said arms with respect to said line so that the diameter of said line will be at all times substantially at least as great as the greatest width of said eye portion.

45 9. The steps in the method of providing a bendable eye portion of wire to an end of a multiple strand wire line which comprise forming from bendable wire a bight and spaced apart arms from said bight to said line, and position-

ing said arms with respect to said line so that the point of juncture of said arms and line will be at substantially diametrically opposite sides of said line.

10. The steps in the method of providing an eye portion on an end of a multiple strand wire line which comprise removing a portion of one of said strands at a point spaced from the end of said line, removing a portion of at least one other of said strands at a point spaced intermediate said first named point and the end of said line, untwisting a strand extending to the end of said line, forming said last named strand into a loop, carrying the free end of said last named strand to the point of severance on said line of said first named strand, and securing said free end to said line at said first point of severance.

15 11. The steps in the method of providing an eye portion on an end of a multiple strand wire line which comprise removing a portion of said strands at a point spaced from the end of said line, removing another portion of said strands at a point spaced intermediate said first named point and the free end of said line, untwisting the strands extending to the end of said line, forming said last named strands into a loop, carrying the free ends of said last named strands to the point of severance on said line of said first named strands, securing said free ends of said last named strands to said line at said point of severance of said first named strands, and welding the remaining free ends of the strands of said line and said last named strands together.

20 12. The steps in the method of providing an eye portion on an end of a multiple strand twisted wire line which comprise removing a portion of said strands at a point spaced from the ends of said line and at substantially diametrically opposite sides of said line, forming legs in a bight in a wire strand, laying the free end portions of said legs in the spaces left by the removal of said first named strands with said bight projecting beyond the extremity of said line, and securing said legs to said line.

25 13. The method of providing an eye portion on an end of a multiple strand twisted wire line which comprises removing a portion of said strands at a point spaced from the end of said line so that an even number of strands remain extending to said end, forming an eye portion from said remaining strands, securing the free ends of said remaining strands together, capping said secured ends, and capping the free ends of said severed strands remaining on said line.
